INTERNAL COMBUSTION ENGINE

Filed Feb. 7, 1925

UNITED STATES PATENT OFFICE

ALOYS N. MALLER, OF OELWEIN, IOWA

INTERNAL COMBUSTION ENGINE

Application filed February 7, 1925. Serial No. 7,681.

This invention relates to an internal combustion engine and the improvement applies particularly to such an engine as is used in connection with electric light plants as used on farms or otherwise. The invention is adapted for application wherever capable of use.

An object of my improvements is to provide means for evacuating deleterious gases from the engine crank-case and into the outer atmosphere without a room or building in which the engine is located, so that such gases will not escape into the room.

The additional object and advantages will become apparent from a consideration of the description following, taken in connection with accompanying drawings illustrating an operative embodiment.

In said drawings:—

Figure 1 is a view in vertical section through an engine illustrating my improvement, and

Figure 2 is a view taken on the line 2—2 of Figure 1.

Figures 3, 4 and 5 are diagrammatic views showing the several important relations of the gas passage valve in the cam shaft relative to the related positions of the crank.

Referring specifically to the drawings, an internal combustion engine of the type used in connection with farm lighting or isolated plants is shown at Figure 1, involving a conventional casting 10 known as the crank case of the engine, in which one or more cranks operate through the internal combustion principle with any suitable fuel supply, igniting and exhausting means. The crankshaft is shown at 13 as having usual connection with a pitman 14, in turn connected to a wrist pin in the piston 12. The tappet or valve chamber of the engine is shown at 15 to house the inlet and exhaust valves which are adapted to be operated by cams 17 on cam-shaft 16. This shaft 16 is journaled in suitable bearings mounted in casting 10 and operated in the usual manner.

To carry out my invention, that part of the camshaft which extends into the bearing sleeve 19 is enlarged as at 18, to give ample room for a port 21 through it, and is jour-

naled in an enlarged bearing 19 mounted in casting 10. At diametrically opposite points, ports 20 are provided in the bearing 19 so designed that they will aline at times with the port 21 in the camshaft. Means of communication 22 opens at one end into one of the ports 20 and at the other end into the interior of the crank case. From the other port 20 a conduit 24 extends passing through the casting 10 and a room wall 26 and preferably terminates exteriorly of the building in which the engine is operating.

As a result of the construction described, an open passage is provided from the interior of the crank case through the conduit 25, chamber 15, conduit 22, bearing ports 20, port in camshaft 21, and conduit 24 to the atmosphere, twice every revolution of the cam-shaft, and as the camshaft is driven one half of the crank shaft speed, this passage is open once every revolution of the crankshaft, and the port 21 is to be timed so that it will be alined with ports 20, to open the passage while the engine piston 12 is half way on its downward stroke. As the engine piston 12 takes its upward stroke the camshaft will have turned so that ports 20 and port 21 will not be in line and passage way will be closed and a partial vacuum will be created in the crankcase.

The advantage of locating the valve structure in the cam shaft and the bearing is in securing regularity in the functioning of the valve as required according to the speed of the engine; to provide an open passage from the interior of the crank-case to the atmosphere during the downward stroke of the piston, said passage being closed during the upward stroke of the piston, without increasing the number of parts required for the engine as is the case with valves now used, thus cheapening the manufacture without increasing the wearing parts of the engine, and with more quiet operation. This valve means is wholly within the crank-case, except the outer termination of the exhaust-pipe 24 to the atmosphere.

It is to be understood that the cam shaft aperture starts to open into communication with the pipe 22 by way of one bearing sleeve 18.

aperture when the piston 12 starts upon its downward stroke and is not fully open until the piston is half way down as shown in Fig. 1, thereafter the cam shaft aperture is closing 5 but is not entirely closed until the piston has reached the bottom of its stroke. The piston when on its downward stroke creates an air compression within the crank-case, as the latter is closed around the inclosed moving elements, which propels the contaminated air 10 through the passages of said elements 15, 22, 19, 18 and 24 to the atmosphere without the building 26.

Various changes may be resorted to providing they fall within the spirit and scope 15 of the invention.

What is claimed is:—

1. In an engine of the class described having a cylinder with ports and cam actuated 20 valves therefor, a reciprocatory piston, a crank shaft, and a pitman connecting the piston and crank shaft, a cam shaft, a crank case surrounding said shafts and opening into one end of the engine cylinder containing 25 said piston, said cam shaft having a transverse port, a fixed bearing sleeve surrounding the part of said cam shaft having said port and having opposite ports registering with the cam shaft port at times, one port being 30 in communication with the crankcase, operative connections between the crank shaft and cam shaft, and a conduit leading from one bearing port through the wall of the crank case.

2. In an engine of the class described, a cylinder having ports, valves therefor, a piston in said cylinder, a crank-shaft, a pitman connecting the piston and crank shaft, a cam-shaft, intermeshed gears on said shafts, cams 40 on said cam shaft for actuating said valves, a crank-case surrounding said shafts and communicating with said cylinder, a chamber above said crank case having a port in its bottom and communicating with the top of the 45 crank case, said cam shaft having below said chamber a transverse passage, a fixed bearing sleeve around said cam-shaft and its said passage and having opposite ports communicating at times with the adjacent ends of said 50 passage, a conduit in communication between one bearing port and the exterior of the crank case, and an open end pipe communicating within the crank case at its lower end with the other bearing port and having its upper 55 end in communication with the bottom of the said chamber.

3. In an engine of the class described, a crank case having communication with the engine cylinder, a crank-shaft in said crank 60 case having operative connections with the piston in said cylinder, said cylinder having ports and valves therefor, a cam shaft in said crank case, operative connections between the crank shaft and cam shaft, a sleeve bearing 65 part of the inner wall of the crank case to

receive an end of said cam shaft, said cam shaft end being diametrically enlarged to fit said bearing part and having within the bearing a transverse passage, said bearing sleeve having opposite ports for occasional 70 registration with the ends of said passage, means of communication between one bearing port and the interior of the crank case, and means of communication between the other bearing port and the exterior of the crank 75 case and also the exterior of the room in which the crank case is housed.

In testimony whereof I affix my signature.

ALOYS N. MALLER.
